UNITED STATES PATENT OFFICE.

CHARLES F. ROPER, OF HOPEDALE, MASSACHUSETTS, ASSIGNOR TO THE DRAPER COMPANY, OF SAME PLACE AND PORTLAND, MAINE.

COP-SKEWER FOR LOOM-SHUTTLES.

SPECIFICATION forming part of Letters Patent No. 588,179, dated August 17, 1897.

Application filed February 26, 1897. Serial No. 625,087. (No model.)

To all whom it may concern:

Be it known that I, CHARLES F. ROPER, of Hopedale, county of Worcester, State of Massachusetts, have invented an Improvement 5 in Cop-Skewers for Loom-Shuttles, of which the following description, in connection with the accompanying drawings, is a specification, like letters on the drawings representing like parts.

10 Cop-skewers or filling-carriers for loom-shuttles have heretofore had their heads provided with unyielding ribs or rings which were adapted to enter grooves in springs carried by shuttles—springs such as represented 15 in United States Patent No. 538,507, dated April 30, 1895—and United States Patent No. 454,811, dated January 23, 1891, shows one old form of cop-skewer.

20 In automatic looms—such, for instance, as the Northrop—the “cop-skewers” or “filling-carriers,” as they are therein designated, are transferred rapidly from the filling-carrier feeder into the shuttle while the loom is in motion, and much trouble has been experienced therein owing to the rapid wearing away of the grooves in the shuttle-springs, that being due to the hard unyielding rings surrounding the head of the skewer or filling-carrier.

25 This present invention has for its object the production of a cop-skewer or filling-carrier the head of which shall be capable of yielding to a limited extent when being inserted into the shuttle between the said springs, such construction greatly reducing the wear of the shuttle-spring grooves. To effect this improvement, the metallic head of the skewer or filling-carrier has been surrounded with a split ring of non-metallic material, preferably wood, and the head of the filling-carrier has been provided with an annular groove in which this split shell or cylinder is located, the shoulders of the groove preventing longitudinal movement of the split ring.

30 Figure 1, in side elevation, represents a cop-skewer or filling-carrier embodying my invention. Fig. 2 is a vertical sectional view

of the head, the blade of the skewer being in elevation. Fig. 3 is a transverse sectional view of the head on the line $x-x$, Fig. 2.

35 The skewer-blade a may be of usual construction, and has secured thereto a metallic head a' , provided at its ends with annular flanges $a^2 a^3$.

40 A non-metallic split shell or cylinder b , preferably of wood, surrounds the head a' between the flanges thereof, and it is annularly grooved, as at b' , to form seats for the encircling metallic split rings c , which enter 45 the usual grooves in the shuttle springs or jaws. These rings retain the non-metallic shell b on the metal head a' , and when the filling-carrier is being forced into the shuttle-springs the split shell, yielding slightly to the 50 pressure, thus greatly reduces the wear on the shuttle-springs.

55 In Patent No. 454,811 referred to a metallic head is surrounded by a wooden ring, and the wooden ring is grooved externally to receive the encircling metallic ring; but in the construction shown in said patent the wooden ring was not split and therefore could not yield, and in said patent the iron head was not grooved annularly to thus receive 60 and retain the wooden shell.

65 It will be seen that the ends of the wooden shell do not abut one against the other, and therefore the shell has a capacity of yielding somewhat under pressure put upon the metallic rings c .

70 Fig. 3 shows the ends of the shell as separated to permit limited amount of yielding of the shell.

Having fully described my invention, what 75 I claim, and desire to secure by Letters Patent, is—

75 1. A filling-carrier provided at its head with a split shell, and having annular ribs surrounding said split shell, substantially as described.

80 2. A filling-carrier having a metallic head, a non-metallic split shell surrounding said head, and annular ribs supported by said split shell, substantially as described.

85 3. A filling-carrier having a split shell sur-

rounding its head, and annular metallic ribs seated in grooves at the periphery of said split shell, substantially as described.

4. A filling-carrier having an annularly-grooved metallic head to leave flanges, a non-metallic split shell located in said annular groove and surrounding the said metallic head between said flanges, and split rings seated in grooves at the periphery of the split

shell, said rings being compressible, substantially as described.

In testimony whereof I have signed my name to this specification in the presence of two subscribing witnesses.

CHARLES F. ROPER.
